UNITED STATES PATENT OFFICE.

GLEN M. DYE, OF MINNEAPOLIS, MINNESOTA, ASSIGNEE TO PAKO CORPORATION, OF MINNEAPOLIS, MINNESOTA, A CORPORATION OF DELAWARE.

PHOTOGRAPHIC-PRINT-WASHING MACHINE.

1,416,402.

Specification of Letters Patent. Patented May 16, 1922.

Application filed March 6, 1920. Serial No. 363,854.

To all whom it may concern:

Be it known that I, GLEN M. DYE, a citizen of the United States, residing at Minneapolis, in the county of Hennepin and State of Minnesota, have invented certain new and useful Improvements in Photographic-Print-Washing Machines; and I do hereby declare the following to be a full, clear, and exact description of the invention, such as will enable others skilled in the art to which it appertains to make and use the same.

My invention has for its special object the provision of an improved machine for washing photographic prints, but the machine may be used for various other purposes.

Generally stated, the invention consists of the novel devices and combinations of devices hereinafter described and defined in the claims.

In the accompanying drawings which illustrate the invention like characters indicate like parts throughout the several views.

Referring to the drawings:

Fig. 1 is a perspective view showing the washing machine with its rotary drum raised;

Fig. 2 is a side elevation with the parts in the same position as shown in Fig. 1; and

Fig. 3 is a section showing, in detail, driving elements and co-operating parts sectioned on the line 3—3 of Fig. 1.

The numeral 4 indicates a water tank of rectangular horizontal section, the same being open at its top and having a rounded bottom. This tank is supported by legs 5, the lower portions of which are connected by transverse and longitudinal tie bars 6 and 7, respectively.

The numeral 8 indicates a cylindrical drum provided in its peripheral shell with a door opening 9 and a hinge door 10 for closing said opening. This door may be secured in a closed position by sliding latches 11 mounted on the drum adjacent to one edge of the opening 9. The cylindrical surface of the drum 8, and preferably also its heads and the door 10 are perforated, so that there will be a continuous and free circulation of the washing water through and within the drum when the latter is rotated.

At its ends, the drum 8 is provided with axially projected trunnions 12 that are removably seated in open notches 13 formed

in lifting heads 14. These lifting heads 14, at their upper ends, are pivotally attached to lifting arms 15 rigidly secured to a rock shaft 16 mounted in suitable bearings 17 on certain of the corner posts or legs 5. The lower ends of the lifting heads 14 are pivotally connected to the free ends of guiding links 18, the lower ends of which are pivoted to one side of the tank 4, at points considerably below the top thereof.

The arms 15 are provided with stop lugs 19 that engage with the upper edge of the ends of the tank 4 and limit the downward movement of the drum to its operative position shown by dotted lines in Fig. 2. One of the trunnions 12 of the drum is provided with a spur gear 20 which, when the drum is lowered to its operative position stated, meshes with a pinion 21 on the inner end of a short shaft 22 that extends through a water tight or packed bearing 23 applied to one of the heads or end plates of the tank 4. The outer portion of the shaft 22, and certain other parts, are located within a housing 24 that is rigidly secured to the above noted head of the tank 4. At that portion of its end that is exposed within the housing 24, the shaft 22 is provided with a worm gear 25 that meshes with a worm 26 on a shaft 27 that is journaled in the lower portion of the housing 24, projects therefrom at one end, and, at its projecting end is provided with a pulley 28. A belt 29 runs over the pulley 28 and over a pulley 30 on the armature shaft of a motor 31, suitably mounted on the base afforded by the tie bars 6 and 7.

The housing 24, as shown, is provided with a removable cover plate 24^a which, when removed, affords access to the interior of the housing and permits lubricating oil or grease to be inserted into the same.

The numeral 32 indicates a foot pedal or lever that is intermediately pivoted on a stud 33 fixed to a bearing 34 on one of the cross bars 33. A coiled spring 35 is placed on the stud 33 and compressed between said lever 32 and a keyed washer 36 on said stud.

The rear end of lever 32 is connected by a lifting rod or vertical link 37 to one of the two lifting arms 15. The front or pedal-equipped end of the lever 32 is adapted to be engaged and locked in its depressed position with the drum in its raised position, as shown in Fig. 1, by a lock dog 38

shown as pivoted to one of the posts 5 and gravity-held yieldingly in an operative position.

The numeral 39 indicates a drum-locking dog in the form of a short arm rigidly secured to the rock shaft 16 and provided with an inwardly bent lock lug 39^a at its free end. The said lock lug 39^a is engageable with the notch of a lug or bracket 40 rigidly secured

10 to the exterior of the drum 8.

The numeral 41 indicates a valve-equipped drain pipe extended from the bottom of the tank 4 and which is normally closed. The numeral 42 indicates an overflow pipe 15 from the tank 4 and the numeral 43 indicates a water supply pipe which leads from a suitable source of water supply and delivers water into the bottom of said tank. Obviously, when water is turned on through 20 pipe 43, the water level in the tank 4 will be maintained at the altitude of overflow pipe 42.

Normally, the drum will be gravity-held in its lowered operative position with its 25 gear 20 engaged with a pinion 21, so that the drum will be rotated when electric motor 31 is in operation, and, under rotation of the drum, the prints therein will be thoroughly washed by the water contained 30 in the tank and continuously circulated through the drum.

After the prints have been washed, the drum may be quickly raised, as shown in the drawings by full lines, simply by stepping 35 on the outer end of the treadle lever 32. When the said lever is depressed, the lock dog 38 will engage and lock the same, thereby holding the drum in its raised position shown in Fig. 1. When the raised drum is 40 thus supported it may be rotated until its door opening is turned upward and positioned, as shown in Figs. 1 and 2, and when so positioned, the lock lug 39^a of lock dog or arm 39 will engage the notch of lug 40, and thereby hold the drum in the position 45 stated and against accidental rotation, while the prints are being removed from the drum or applied therein.

When the drum is to be lowered to operative position, the operator simply kicks the dog 38 out of engagement with the lever 32, thereby permitting the drum to lower under the action of gravity. When the drum moves downward, the notched lug 40 55 disengages itself automatically from the lug of lock dog 39.

When the drum is raised, as shown in Fig. 1, it may, when desired, be lifted entirely from its supporting heads 14, inasmuch as 60 its trunnions 12 are freely disengageable from open trunnion seats 13.

In actual practice, this machine has been found highly efficient for use in washing photographic prints, and obviously, its washing capacity is very large, inasmuch as a

large number of prints can be placed in the drum at one time. Moreover, the washing of the prints is complete and the prints in the washing action are never roughly handled, nor will they be folded or creased, 70 but will be kept floating in the water and all of the hypo will be removed from the prints.

What I claim is:

1. In a machine for washing photographic prints and the like, the combination with a tank, of a rotary perforated drum working therein, and lever-actuated connections for lifting the drum out of working position and for returning the same to working position.

2. In a machine for washing photographic prints and the like, the combination with a tank, of a rotary perforated drum working therein, lever-actuated connections for lifting the drum out of working position and for returning the same to working position, and a lock operative to hold said drum against rotation when raised, the said lock being automatically released by lowering 90 movement of the drum.

3. In a machine for washing photographic prints and the like, the combination with a tank, of a rotary perforated drum working therein, lever-actuated connections for lifting the drum out of working position and for returning the same to working position, a driving pinion for said drum, and a gear mounted on one end of said drum and arranged to be moved into and out of mesh 100 with said pinion by movements of said drum, respectively, to and from operative position.

4. In a machine for washing photographic prints and the like, the combination with a tank and a perforated rotary drum operated therein, of supporting heads to which said drum is journaled at its ends, a rock shaft having arms connected to said heads for vertically moving the same, and lever operated connections for oscillating said rock shaft.

5. In a machine for washing photographic prints and the like, the combination with a tank and a perforated rotary drum operated therein, of supporting heads to which said drum is journaled at its ends, a rock shaft having arms connected to said heads for vertically moving the same, lever operated connections for oscillating said rock shaft, 110 said arms having stops engageable with the upper edge of said tank to limit the downward movement of said drum, and means for rotating said drum when in operative position.

6. In a machine for washing photographic prints and the like, the combination with a tank and a perforated rotary drum operated therein, of supporting heads to which said drum is journaled at its ends, a rock 130

shaft having arms connected to said heads for vertically moving the same, and lever operated connections for oscillating said rock shaft, the journal connections between said 5 drum and lifting heads comprising trunnions on said drum, and open seats in said heads, whereby said drum may be readily removed from said heads.

7. In a machine for washing photographic prints and the like, the combination with a tank and a perforated rotary drum operated therein, of supporting heads to which said drum is journaled at its ends, a rock shaft having arms connected to said heads for 10 vertically moving the same, lever operated connections for oscillating said rock shaft, and a drum locking dog on said rock shaft having an interlocking engagement with said drum when the latter is raised and serving to prevent accidental rotation thereof, the said drum having a peripheral door opening that is turned upward when said drum is raised and locked against rotation by said lock dog.

25 8. In a machine for washing photographic prints, and the like, the combination with a tank, of a rotary perforated drum working therein, a rock shaft having a pair of projecting arms, drum supporting heads hung 30 from the ends of said arms, said drum, at its ends, being journaled to said head, links connecting the lower ends of said heads to the interior of said tank, and a foot-actuated lever having a connection to said rock shaft 35 for oscillating the same to raise and lower said drum.

9. In a machine for washing photographic prints, and the like, the combination with a

tank, of a rotary perforated drum working 40 therein, a rock shaft having a pair of projecting arms, drum supporting heads hung from the ends of said arms, said drum, at its ends, being journaled to said head, links connecting the lower ends of said heads to the interior of said tank, a foot-actuated 45 lever having a connection to said rock shaft for oscillating the same to raise and lower said drum, a power driven pinion positioned within said tank at one end thereof, and a gear carried by one end of said drum and 50 movable into and out of mesh with said pinion by movements of said drum.

10. In a machine for washing photographic prints, and the like, the combination with a tank, of a rotary perforated drum 55 working therein, a rock shaft having a pair of projecting arms, drum supporting heads hung from the ends of said arms, said drum, at its ends, being journaled to said head, links connecting the lower ends of said heads 60 to the interior of said tank, a foot-actuated lever having a connection to said rock shaft for oscillating the same to raise and lower said drum, and journals between said drum and supporting heads being afforded by open 65 seats in said heads and trunnions on said drum.

11. In a machine for washing photographic prints and the like, the combination with a tank, of a rotary perforated drum 70 working therein, and means for lifting the drum out of working position and for returning the same to working position.

In testimony whereof I affix my signature.

GLEN M. DYE.
